John Thomas Williams
Attest: ## UNITED STATES PATENT OFFICE.

JOHN THOMAS WILLIAMS, OF LIVERPOOL, ENGLAND.

WRENCH.

SPECIFICATION forming part of Letters Patent No. 793,257, dated June 27, 1905.

Application filed September 27, 1904. Serial No. 226,172.

To all whom it may concern:

Be it known that I, JOHN THOMAS WILLIAMS, a subject of the King of Great Britain, residing at 131 Lambeth road, Liverpool, in the county of Lancaster, England, have invented new and useful Improvements in Wrenches, of which the following is a specification.

This invention has reference to wrenches for turning pipes, nuts, rods, and the like; and it relates more particularly to that type which comprises two limbs, one comprising an upper jaw and a stem and the other the lower jaw and a stem, the two being jointed by a joint-pin passing through both and forming a hinge below the face of the lower jaw. According to the present invention a wrench of this kind is so constructed that the one jaw may be adjusted in relation to the other so as to take different sizes of pipes, nuts, or the like without the necessity of withdrawing the hinge-pin, which in this case is or may be permanent and fixed in one of the limbs, while the stem of the other limb or jaw is provided with a plurality of gaps or sockets, which form so many centers for the hinge-pin to be moved to and rest in to adjust the wrench or spanner for taking different sizes of articles.

In the drawings, Figure 1 is a side view, partly in section, of the wrench. Fig. 2 is a like view of a modification. Figs. 3 and 4 are further modifications.

Referring to the drawings, one limb consists of an upper jaw 1 and a stem 2 and the other consists of the lower jaw 6 and stem 7, and these two limbs are held together and work in relation to each other upon and about a joint hinge-pin or pivot 5, which passes through both limbs.

The stem 2 in the construction shown in Figs. 1, 2, and 3 is provided with a longitudinal slot 3, having a plurality of gaps or notches 4 leading out of it, forming so many centers or sockets for the hinge-pin 5 to be moved to and rest in to adjust the spanner or wrench for taking different sizes of articles, and the pin is held in one of the sockets or gaps by the spring 9, which prevents the two limbs from moving away from each other and the pin coming out of the sockets at all times.

The lower jaw-limb 7 is made of sheet 50 metal folded over so that the two cheeks lie one on either side of the other limb-stem 2, and the hinge-pin 5, which may be a rivet, screw, or a bolt and nut, passes through these cheeks. 55

In the construction shown in Figs. 1 and 2 the spring 9 is fastened in the channel of the outer limb, in Fig. 1 it being fastened to the block 8, which lies between the end of the cheeks of the lower jaw-limb, forming the jaw 6, where they are fastened together, while in Fig. 2 it is fastened to the back of the stem 7 by a removable screw-pin 10. In the former case the sockets or notches 4 lie on one side of the slot 3, and in the other case they lie 65 on the opposite side of the slot, and this constitutes the chief difference between the two constructions of spanners.

In Fig. 3 the shape of the sockets or gaps 4 is curved, and the metal of the lower part 70 is carried up so that the pin 5 will lie and be held behind this carried-up part or hook-lip and will not come out of the recess or socket of itself.

In the modified construction shown in Fig. 4 75 the gaps or pivot-notches 4 are formed in the edge of one of the limbs of the wrench in lieu of the center of it, as in the other form shown.

What is claimed is—

1. A wrench comprising a shank having an 80 outer jaw thereon, said shank being provided with a slot having a plurality of gaps therein, a second shank of channeled form having its sides at one end curving upwardly so as to form two jaws between which the first-men- 85 tioned shank fits, a pivot passing through both sides of the second shank and engaging any one of the gaps in the first shank and a spring secured in the channeled shank and engaging with the first-mentioned shank. 90

2. A wrench comprising a shank having an outer jaw thereon, said shank being provided with a plurality of gaps, a second shank of channeled form, having a jaw thereon, a pivot passing through both sides of the second 95 shank, and engaging any one of the gaps in the shank, and a V-spring in the channel-shank having an eye at its lower end, and dis-

posed between the back of the other shank, and the back of the channel-shank, and engaging with the back of the first-mentioned shank, and adapted to press it toward the pivot, and a screw-pin passing through the two sides of the channel-shank and the eye of the spring, substantially as described.

In testimony whereof I have signed my name to this specification in the presence of two subscribing witnesses.
